UNITED STATES PATENT OFFICE.

SAMUEL BUTTERWORTH, OF BOSTON, MASSACHUSETTS.

CLOTHES-DRIER.

SPECIFICATION forming part of Letters Patent No. 744,901, dated November 24, 1903.

Application filed September 15, 1902. Serial No. 123,365. (No model.)

To all whom it may concern:

Be it known that I, SAMUEL BUTTERWORTH, a citizen of the United States, residing at Boston, in the county of Suffolk and State of Massachusetts, have invented certain new and useful Improvements in Clothes-Driers, of which the following is a specification, reference being had therein to the accompanying drawings.

10 Figure 1 is a vertical central section at a line corresponding to line 1 1 of Fig. 3 of my clothes-drier. Fig. 2 is a top plan view of a portion thereof. Fig. 3 is a view, partly in cross-section at line 3 3 of Fig. 1, showing a detail of the telescopic construction of the standard of the drier and a top plan view of the adjusting mechanism. Fig. 4 is a top plan view of the special cover and spider combined. Fig. 5 is a perspective of a stove provided with my clothes-drier.

The object of my invention is to produce a special stove-hole cover adapted to hold the standard of a clothes-drier or the like in vertical position.

25 In the drawings, 1 is a special stove or range cover adapted to be substituted for one of the regular covers, and 2 is a standard-receiving socket formed on cover 1, which is formed with a fastener-hole 3, through which 30 a fastener 4 extends into connection with the spider 5, which is preferably made up of a central boss and a plurality of projecting arms, as shown. Outer portion 6 of the spider projects beyond the under peripheral margin of the 35 cover-hole in the stovepipe 8, the spider being inserted within the stove underneath the cover-hole in which cover 1 is to be set. When the cover is in place, fastener 4 is passed through the hole 3 into the spider, and 40 the latter thereby locked in position on the stove or range. Cover 1, with its standard-receiving socket 2 and the spider, and the means for connecting the cover and spider together and to the stove may be made in a variety 45 of forms, according to preference, without departure from my invention, a wholly new feature whereof consists in mounting a clothes-drier on a substitute imperforate stove-cover, which is anchored to the stove so as to hold

the standard, or for the standard of any other 50 device which is to be held vertically above the stove-top. By making the stove-hole cover imperforate smoke, dirt, and gases cannot pass through the cover. The socket 2 constitutes one form of coupling member 55 whereby the cover and the standard of the drier or other device are detachably secured together.

Any desired kind of clothes-drier having a standard may be used; but I prefer to use one 60 containing features of my present construction, as follows: A hollow tube 10, the lower end of which fits tightly in the standard-receiving socket, forms the lower member of the telescopic standard. The upper member 11 65 thereof is a suitable slide-bar, formed with a row of recesses 12, which are opposed to a slot 13 in the tube 10. A bracket 14, fast on the tube 10, supports a cross stud or journal 15, carrying a fast spur-wheel 16, the teeth 17 70 whereof work in the recesses 12. Journal 15 also has a handle 18 fast on it. The stud 15 is loosely mounted in the bracket. By turning the handle the spur-wheel is rotated and the slide-bar 11 raised or lowered in the lower 75 member. A pawl 19, pivoted at 20 on the bracket 14, engages the teeth of the spur-wheel to hold it in adjusted position.

The upper end of the slide-bar is provided with a reel-bearing shoulder 20^a. The reel 80 21, which may be of many different forms, is provided with hub 22, having a recess to receive the upper end of the slide-bar on which the reel rotates, resting on the shoulder 20^a. The reel comprises a plurality of radial arms 85 23, each having an upturned lateral hook 24 at its outer end. Fast on the under side of the arms, concentric with the hub, and of a radius less than the length of the arms there is a rib 25, the exposed parts whereof between 90 the arms afford anchorages at 26 for the inner hook-shaped ends of the dry-bars 27, the lateral hooks 24 at the ends of the arms holding the dry-bars in supporting position when the dry-bars hooked on the anchorages 26 rest in 95 the hooks 24. When the dry-bars are on the anchorages and not also on the hooks, they hang downwardly.

Cover 1 forms a base-plate for the drier.
What I claim is—

The combination of a clothes-drier stand-
ard; a stove-hole cover having a downwardly-
5 projecting, standard-receiving socket which
is imperforate; means for holding said cover
in place on a stove; and means for detach-
ably connecting said holding means to the
under side of the cover; said holding means

comprising projections extending beyond the 10
periphery of the cover.

In testimony whereof I affix my signature
in presence of two witnesses.

SAMUEL BUTTERWORTH.
